EXHAUST SILENCER

Omer J. Rainville, South Attleboro, Mass.

Application February 17, 1943, Serial No. 476,220

4 Claims. (Cl. 181—58)

This invention relates to certain new and useful improvements in exhaust silencers and of the type generally employed with internal combustion engines for silencing or muffling the discharge of products of combustion from such engines.

The primary object of the invention is to provide an exhaust silencer especially designed for use in connection with internal combustion engines and in which the explosive force of the exhausting products of combustion is dissipated or broken down into a multiplicity of relatively smaller blasts for the purpose of quieting the exhaust discharge and removing back pressure on the engine.

A further object of the invention is to provide an exhaust silencer of the foregoing character wherein the housing of the silencer has an exhaust pipe section from the engine entering the same, with said pipe section provided with a plurality of openings of gradually increasing sizes from the inlet end thereof toward the outlet with such openings arranged in circular series and with the series staggered for the lessening of noise incident to the flow of products of combustion therethrough and for eliminating back pressure on the engine.

With the above and other objects in view that will become apparent as the nature of the invention is better understood, the same consists in the novel form, combination and arrangement of parts hereinafter more fully described, shown in the accompanying drawings and claimed.

In the accompanying drawings:

Figure 1 is a longitudinal sectional view of an exhaust silencer for internal combustion engines, the center exhaust pipe within the outer casing being illustrated in elevation and showing openings therein of gradually increasing sizes toward the discharge end.

Figures 2, 3 and 4 are cross-sectional views taken on lines 2—2, 3—3 and 4—4 of Figure 1, showing the flutes gradually struck greater distances inwardly to provide increased resistance to the flow of products of combustion and increased sizes of lateral discharge openings.

Figure 5 is a cross sectional view taken on line 5—5 of Figure 1, showing the laterally apertured partition wall in the casing to which the adjacent end of the center exhaust pipe is connected.

Figure 6 is a cross-sectional view taken on line 6—6 of Figure 1, showing the second partition wall with lateral discharge openings therein offset 90° with respect to the partition wall shown in Figure 5.

Figure 7 is a detail sectional view taken on line 7—7 of Figure 1, and

Figure 8 is a fragmentary longitudinal sectional view of the center exhaust pipe, the axial line thereof being indicated by dot and dash lines and showing the flutes increasingly bent toward said axial line in a direction toward the discharge end of the exhaust pipe.

Referring more in detail to the accompanying drawings, the exhaust silencer comprises a casing 10 preferably of cylindrical formation and having closed front and rear end walls 11 and 12 respectively, the front end wall 11 being provided with a center opening surrounded by a bearing collar 13 for the support of an exhaust pipe 14 while the rear end wall 12 of the casing has a central opening therein surrounded by bearing collar 15 for the mounting of an outlet pipe 16 exhausting to atmosphere.

The exhaust pipe 14 extends into the casing 10 the desired distance which may approximate substantially two-thirds the length of the casing and finds support at its rear end on a partition wall 17 extending transversely of the casing 10 and 25 having a marginal flange anchored as at 18 to the wall of the casing. The connection between the rear end of the exhaust pipe 14 and partition wall 17 is shown more clearly in Figures 1, 5 and 7 as comprising a base disk 19 having an annular flange 20 received in the adjacent end of the exhaust pipe 14 and secured thereto as at 21 by rivets or like fastening elements, the base disk 19 being anchored to the partition wall 17 by means of rivets 22 or the like. As shown in Figures 1 and 5, the partition wall 17 has a pair of openings 23 respectively positioned laterally of the exhaust pipe 14. A second partition 24 extends transversely of the casing 10 substantially midway between the cross partition 17 and the

40 rear end wall 12, said partition 24 having a marginal flange that is anchored as at 25 to the casing 10 and is further provided with a pair of transversely aligned openings 26 respectively at opposite sides of the longitudinal axis of the casing 10 and at a 90° turn from the openings 23 in the partition 17, the relationship of the openings 23 and 26 in the partitions 17 and 24 being illustrated in Figures 5 and 6.

The exhaust pipe 14 is provided with circular 50 series of openings throughout its length within the casing and said openings are arranged in groups with the openings of each group successively increasing in size toward the partition wall 17 and in the production of these openings, lugs, ears or flutes are struck inwardly of the exhaust

pipe with such flutes of the respective groups gradually extending nearer toward the longitudinal axis of the exhaust pipe in a direction toward the partition wall 17. The openings of each circular series are in staggered relation with respect to the openings in adjacent series, the openings 21 being formed by the inwardly struck flutes 28 and upon an inspection of Figures 2 to 4 and 8 it will be observed that the openings 21 increase in size in a direction toward the partition wall 17 and that the flutes 28 are of correspondingly increased lengths, Figure 2 showing the smaller openings and shorter flutes, Figure 3 showing larger flutes approaching the longitudinal axis of the exhaust pipe, while Figure 4 shows the flutes 28 contacting at their apices at the longitudinal axis of the exhaust pipe.

It will be understood that least impediment is offered to the flow of exhaust products of combustion through the exhaust pipe 14 at the point of entry of the products into the pipe, the smaller openings 21 permitting the lateral escape of some gases into the casing 10, while impediment of flow is gradually increased as will be understood from an inspection of Figures 3 and 4 of the drawings, by the increased areas of the flutes 28. The gradual increase in size of the openings 21 and the resistance offered by the inwardly struck flutes that increase in area tends to deaden the noise incident to an exhaust and to relieve back pressure on the engine. The exhaust gases outletting through the openings 21 into the chamber 29 of the casing follow the direction of flow indicated by the arrow lines and pass through the openings 23 in the partition 17 and then through the openings 26 in the partition 24 for outletting through the pipe 16 to atmosphere.

From the above detailed description of the invention it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:

1. In an exhaust silencer of the character described, a casing, an exhaust pipe entering one end of the casing and terminating in spaced relation to the other end of the casing, a cross partition in the casing closing the inner end of the exhaust pipe and having openings therein laterally of the pipe, and said pipe having openings gradually increasing in size in a direction toward said partition, and said openings being formed by inwardly struck flutes with the flutes

gradually increasing in length and approaching the longitudinal axis of the exhaust pipe in a direction toward said partition.

2. In an exhaust silencer of the character described, a casing, an exhaust pipe entering one end of the casing and terminating in spaced relation to the other end of the casing, a cross partition in the casing closing the inner end of the exhaust pipe and having openings therein laterally of the pipe, and said pipe having openings gradually increasing in size in a direction toward said partition, and a second partition in the casing between the first-named partition and the outlet end of the casing and having openings therein out of line with the openings in the first-named openings in the first-named partition, and said openings being formed by inwardly struck flutes with the flutes gradually increasing in length and approaching the longitudinal axis of the exhaust pipe in a direction toward said partition.

3. In an exhaust silencer of the character described, a casing, an exhaust pipe entering one end of the casing and terminating in spaced relation to the other end of the casing, a cross partition in the casing closing the inner end of the exhaust pipe and having openings therein laterally of the pipe, and said pipe having openings gradually increasing in size in a direction toward said partition, and said openings being formed by inwardly struck flutes with the flutes gradually increasing in length and approaching the longitudinal axis of the exhaust pipe in a direction toward said partition, the flutes adjacent the partition contacting on the axis line for directing the products of combustion through said openings.

4. In an exhaust silencer of the character described, a casing, an exhaust pipe entering one end of the casing and terminating in spaced relation to the other end of the casing, a cross partition in the casing closing the inner end of the exhaust pipe and having openings therein laterally of the pipe, and said pipe having openings gradually increasing in size in a direction toward said partition, and a second partition in the casing between the first-named partition and the outlet end of the casing and having openings therein out of line with the openings in the first-named openings in the first-named partition, and said openings being formed by inwardly struck flutes with the flutes gradually increasing in length and approaching the longitudinal axis of the exhaust pipe in a direction toward said partition, the flutes adjacent the partition contacting on the axis line for directing the products of combustion through said openings.

OMER J. RAINVILLE.
